PACKING HOLDER FOR CAR JOURNALS

Claude Wilson, Duquoin, Ill.

Application May 6, 1942, Serial No. 441,917

3 Claims. (Cl. 308—89)

This invention relates to packing holders for railway car journals. In such journals the oil soaked cotton or waste material used for packing the journal boxes of the wheel axles, is placed in the boxes immediately below the journals and at the sides thereof up to a point about one inch below the center lines of the journals, leaving a space of about two inches intervening at each side, between the surface of the packing and the bearing brasses or bushings superposed on the upper sides of the journals.

In practice the said packing or waste used for this purpose, frequently works up the sides of the journal and underneath the bushings, carrying with it particles of dust or grit and causing "hot boxes." The result is a very considerable increase in the labor and cost of up-keep, replacement and reconditioning of packing and journals.

It is the prime object of this invention to provide a simple and effective means for holding the packing in proper position in the lower part of the box and so preventing it from working into the bearings or out at the front of the boxes.

More specifically the object is to provide an outer cross head for positioning at the front of the journal box within the lid, the same having a pair of spaced and parallel arms extended therefrom and adapted for insertion into the journal box at each side of the journal, within the lateral spaces between the margins of the bushing and the packing below, thus serving to hold the packing down in place.

A further object is to add to the specific structure last described, wings or leaves hinged to the inner sides of the said arms and arranged to resiliently press against the sides of the journal, for assisting in holding the packing down in place.

A preferred embodiment of the invention is shown in the drawing, wherein:

Figure 1 is a perspective view of a packing holder constructed in accordance with this invention.

Figure 2 is a vertical section through a standard form of journal box assembly, showing the packing therein, the superposed brass or bushing, the wedge above the bushing, and my packing holder inserted above the packing, in the space between the margins of the bushing and the packing, the journal being indicated in dotted lines at the outer broken off end of the car axle.

Figure 3 is a section on the line 3—3 of Figure 2.

Figure 4 is a section on the line 4—4 of Fig-

ure 2, same being drawn on a greatly enlarged scale.

Referring more particularly to the drawing, the reference character A designates a conventional car journal box as mounted in the pedestal B of a usual form of railway car truck (not shown), and said journal box acting as a closure over and lubricating means for the journal C as conventionally formed at the outer end of the axle, D, outwardly of the wheel (not shown). The journal is flanged on its end as at Ca, and passes into the box through an opening E formed through the inner end of the box. The outer end of the box A is closed by a lid F hinged upwardly at G to the upper margin of the box, and spring set at H to close against the lower upturned lip I.

By raising the lid F oil soaked waste or packing J is inserted in the lower part of the box to lubricate the journal C. The packing J fills the box to a point about one inch, more or less, below the center line of the journal C. A brass or other metal bushing K, arcuate in cross section on its lower side, complementally to the curve of the journal C, is seated upon the upper side of the journal, and a wedge block L is then forced inward over the top of the bushing K and is braced between the bushing and the top of the box A. The described assembly and relation of parts is clearly shown in Figure 3, and is conventional art.

An inspection of Figures 2, 3 and 4 discloses that between the upper surface of the packing J below and the lateral margins of the bushing K above, there is at each side a substantial clearance space M, and in practice my invention makes use of this space.

The invention comprises an elongated cross-head 5 for positioning within the lid of the box A, horizontally across the flanged end Ca of the journal, and provided with a pair of elongate, flat, spaced and parallel arms 6 extended therefrom and adapted for insertion into the lateral clearance spaces M at each side of the journal C, 45 where they rest directly upon the packing J. The lower margins of the arms 6 are inturned as at 6a, to afford a broader seating upon the packing.

Elongate press wings or leaves 7 are hinged by their upper margins to the upper margins of the arms 6, in the mortised method shown at 8, where the sleeved and dove-tailed margins are linked together by pins 9 passed therethrough in a conventional manner. Coil springs 10 are seated on 55 studs 11 between the arms 6 and wings 7, and

normally urge the wings 7 inwardly against the journal C. The lower margins of the wings 7 are out-turned as at 7a to freely overlap the inturned margins 6a of the arms 6. The wings 7 are cut away at their outer ends as shown at 7b, to clear the flanged end Ca of the journal C.

A skirt strip 12 is anchored at 13 to the lower margin of the cross-head 5 and is flared downward and outward to meet the inner face of the upturned lip I of the box A, inside the lid F, when the device is inserted in place. This skirt strip prevents packing waste from working out of the box.

A handle 14 is riveted at 15 centrally to the outer face of the strip 12, and is cut away at one side as at 14a to pass the shank of a latch 16 hinged by its upper end, as at 17, to the upper free end of the handle 14. The latch shank is also cut away on one side, as at 16a, so as to nicely play within the recessed portion 14a of the handle 14, in the operation of the device. The lower extremity of the latch 16 is inturned, as at 16b, to close under the lip I of the box, for holding the device in proper position. A retractile coil spring 18 is seated between the elements 14 and 16, with its ends anchored to these elements, and serves to normally urge the latch 16 inward to its closed position. In practice, the packing J is inserted in the lower portion of the box A, and then the arms 6, with wings 7 attached, are inserted into the lateral spaces M, in manner previously described. The arms and wings bear down upon the packing and prevent its displacement, as stated.

Any desired modifications may be made in the described structures, within the scope of the claims.

I claim:

1. In a device of the kind described for insertion on top of packing as laid in the base of a car journal box and extended partially up the sides of a journal extended through the box, a cross-head for positioning across the outer end of the journal, spaced arms extended from the cross-head for insertion into the journal box above the packing therein for holding the same in place, wings hinged to the said parallel arms and depended over the inner sides thereof, the lower margins of the arms and wings being turned into overlapping relation one over the other, and means for resiliently urging the wings towards the sides of the journal.

2. In a device according to claim 1, latching means on the cross-head for releasably securing the device in place.

3. In a device of the kind described for insertion on top of packing as laid in the base of a car journal box and extended partially up the sides of a journal extended through the box, a cross-head for positioning horizontally across the outer end of the journal, spaced and parallel arms extended from the cross-head and arranged for insertion into the journal box at each side of the journal and upon the packing therein for holding the same in place, wings hinged to the upper margins of the said parallel arms and depended downwardly over the inner sides thereof, the lower margins of the arms and wings being turned perpendicularly into overlapping relation one over the other, means for resiliently urging the wings towards the sides of the journal, and latching means on the cross-head for releasably securing the device in place.

CLAUDE WILSON.
